NOZZLE TIP FOR A DENTAL INSTRUMENT

William B. Dragan, R.F.D. Burr St.,
Fairfield, Conn. 06430

Filed Oct. 1, 1970, Ser. No. 25,298

Term of patent 14 years

Int. Cl. D24—99

U.S. Cl. D24—1

FIG. 2

FIG. 3

FIG. 1

FIG. 4

FIG. 6

FIG. 7

FIG. 5

FIG. 8

FIG. 1 is a side elevation view of a nozzle tip for a dental instrument showing my new design.

FIG. 2 is a top plan view thereof.

FIG. 3 is a left end view thereof.

FIG. 4 is a side elevational view thereof, and

FIG. 5 is a side elevation view of a second embodiment of the nozzle tip illustrated in FIG. 1.

FIG. 6 is a top plan view thereof.

FIG. 7 is a left end view thereof.

FIG. 8 is a right end view thereof.

I claim:

The original design for a nozzle tip for a dental instrument, substantially as shown and described.
